UNITED STATES PATENT OFFICE.

IVOR D. THOMAS, OF CLEVELAND HEIGHTS, OHIO, ASSIGNOR TO THE WELLMAN-SEAVIER-MORGAN COMPANY, OF CLEVELAND, OHIO, A CORPORATION OF OHIO.

METHOD OF FORGING INGOTS, BILLETS, AND THE LIKE.

Application filed November 2, 1920. Serial No. 421,265.

To all whom it may concern:

Be it known that I, IVOR D. THOMAS, a citizen of the United States, residing at Cleveland Heights, in the county of Cuyahoga and State of Ohio, have invented a certain new and useful Improvement in Methods of Forging Ingots, Billets, and the like, of which the following is a full, clear, and exact description.

10 This invention relates to a method of forging ingots or billets, and work of like nature.

Heretofore forgings have been made from ingots or billets worked under a hammer or press of the vertical type. This required holding the piece being worked in a substantially horizontal position which has always presented more or less of a problem, depending upon the size of the piece worked, for 20 as is well known by those engaged in the production of heavy forgings, the manipulation of the ingot or billet has not only been exceedingly difficult, but it required the services of many men.

25 In accordance with the present invention a horizontal press or hammer is utilized, and the ingot or billet is held in a vertical position while being worked, preferably by means of a crane with suitable provision for 30 hoisting and lowering the forging, for rotating it about a vertical axis, and for moving it horizontally.

In the drawings which show one embodiment of apparatus which may be employed 35 to advantage in carrying out my improved method, Fig. 1 shows one view of an overhead crane employed for handling the work, and of a horizontal press used in conjunction therewith; Fig. 2 is a view taken at right 40 angles to Fig. 1; Fig. 3 is a fragmentary view on a large scale, showing more of the details of the crane; Fig. 4 is a plan view of the press; Figs. 5 and 6 are side views, one taken at right angles to the other, showing 45 the preferred ingot or billet gripping mechanism.

Referring now to the drawings, although 50 it is not essential that the ingot or billet be supported by a crane of the overhead type, that type of crane lends itself very well to the problem at hand, and for that reason is shown in the drawings. The crane here shown includes a traveling bridge 10, movable along tracks 11, supported on a 55 structure 12. The range of movement of

the bridge is preferably such that the ingots or billets can be conveyed from the soaking pit or heating furnace to the press in which they are forged, and if desired, also to the machine tools in which the forged pieces are 60 machined subsequent to the forging operation.

On the bridge is mounted a traveling trolley 13 on which is a rotatable carriage 14 adapted to be rotated about a vertical axis, 65 and carrying a hoisting mechanism 15. From the hooks of this hoisting mechanism is supported suitable gripping mechanism 16, for engaging and supporting while in a vertical position, the ingot or billet 17 to be 70 forged.

With this crane or other suitable mechanism by which the work 17 can be supported vertically, is employed a horizontal press 18 which can be substantially of standard form, 75 except it is arranged horizontally instead of vertically as has always been the case heretofore. The press is shown only conventionally in the drawings, but it will include a stationary base or anvil 19 and a 80 reciprocating head 20 which can be operated with a horizontal stroke by any suitable means such as hydraulically, or by any other motive fluid or power means.

It is important, of course, that the work 85 be capable of being lowered from above in an endwise direction between the base or anvil 19 and the head 20, and to provide room for lowering the work for substantially its full length between the anvil and 90 the reciprocating head, a pit 21 is provided beneath the press.

Though the details of the crane are not material to the present invention, I might mention that if an overhead crane is employed, as shown in Figs. 1 and 3, the trolley 13 may be moved lengthwise of the bridge 10 by a suitable motor such as indicated at 22 in Fig. 3, and the rotatable carriage 14 can be rotated by a suitable motor indicated 95 at 23.

Likewise, the ingot gripping mechanism 16 may be other than shown, and in Figs. 5 and 6 I have shown a construction which answers the requirements very effectively. 105 In this instance the ingot or billet is adapted to be gripped on opposite sides by a pair of cam shaped grippers 24, mounted centrally on a pair of shafts 25, whose ends are journaled in a frame 26, through which 110

the body of the ingot or billet is adapted to extend. The ends of these shafts are provided with pinions 27 which are connected by idler pinions 28, to vertically movable racks 29, to which the hoisting mechanism 15 is connected. It will be seen that if these racks are pulled upwardly by the hoisting mechanism, the cam shaped grippers 24 are rotated so as to tightly engage or grip the work to be forged, whereas, if the frame of the gripping mechanism is elevated, as by means of ropes, not shown, connected to eyes 30, the shafts carrying the grippers will be rotated in the reverse direction so as to release the work. The hoisting mechanism 15 may include a lower block 31 adapted to be hooked to the rack bars 29, and an upper block 32. These blocks may have as many sheaves as necessary, and the sheaves will be traversed by a hoisting rope or cable 33 adapted to be wound onto, and unwound from a drum, indicated at 34 in Fig. 3, and driven by a motor 35. The drum and motor are mounted on the revoluble carriage 14, and the upper block 32 will be connected to the center or axis of this carriage as shown in the drawings.

With this mechanism the work can be moved laterally, can be raised and lowered, and can be turned about a vertical axis, these being all the movements necessary to enable a piece being effectively forged in the horizontal press. All these motions, together with the operation of the press, may be under the control of one operator, and in case the manipulator is in the form

of an overhead crane as herein illustrated, a double form of control may be provided so that the operator in the operator's cab of the crane may deliver the work over the press and may then by operating one or more switches put the control of the crane under the operator of the press. The operator of the press will then by suitable control instrumentalities be able not only to operate the press but give to the work all the necessary movements, which include raising and lowering the work, moving it laterally, and turning it, so that it can be forged in the desired manner while continuously supported from above.

By this method the usual difficulties and the major portion of the manual labor attending the manipulation of large forgings while they are being forged is eliminated, and the forging can be done effectively and with greater speed, and at lower cost than heretofore.

Having described my invention, I claim:

The method of making forgings which comprises suspending an ingot or billet in vertical position from an overhead support capable of moving the ingot or billet laterally, up and down, and rotating it about a vertical axis, forging the ingot or billet, while thus supported, in a horizontal press, and manipulating the work by raising or lowering the same or by rotating it about its axis as may be necessary during the forging operation.

In testimony whereof, I hereunto affix my signature.

IVOR D. THOMAS.
